AUXILIARY STARTING MEANS FOR INTERNAL COMBUSTION ENGINES

Filed July 26, 1924

UNITED STATES PATENT OFFICE

CHARLES FREDERICK HEYWOOD, OF DETROIT, MICHIGAN, ASSIGNOR TO SKY SPECIALTIES CORPORATION, OF DETROIT, MICHIGAN, A CORPORATION OF MICHIGAN

AUXILIARY STARTING MEANS FOR INTERNAL-COMBUSTION ENGINES

Application filed July 26, 1924. Serial No. 728,339.

This invention has reference to the self starters of engines, and more particularly those of the type in which the starting of the engine is effected by the admission of fluid under pressure to the cylinders thereof in order to cause the actuation of the pistons. It is, of course, necessary in such cases that the cranks with which such pistons cooperate shall pass or be caused to pass beyond the dead center or an ordinarily inoperative position in order that the fluid under pressure may be enabled to impart the necessary motion to the said cranks, but it often occurs, especially in one or two cylinder engines, that the cranks come to rest on dead centers and consequent difficulty in starting is encountered.

It is, therefore, the purpose of this invention to provide auxiliary means for the purpose of relieving such a situation by imparting initial movement to the engine crank shaft so that such dead center may be passed and the self starter permitted to carry out its functions in the desired manner; and it is also an object of said invention to provide such means which may be actuated by fluid under pressure preferably drawn from the same source of fluid effecting the starting of the engine.

A further object is to provide means whereby the auxiliary starting device may be also utilized as a compressor for the re-charging of a reservoir forming a storage member for the starting fluid; a still further object being to provide a valve controlled piston operated device coupled to the crank shaft of an engine and adapted to initially operate said engine to facilitate the starting thereof and to be operated by said engine to effect the compression in a receiver of a starting fluid.

Still further objects subsidiary to or resulting from the aforesaid objects, or from the construction or operation of the invention as it may be carried into effect, will become apparent as the said invention is hereinafter further disclosed.

The said invention may be carried into effect by providing an engine with starting means comprising a storage device for fluid under pressure connected by valve controlled

pipes or passages communicating with the cylinders of the engine through which fluid from the storage tank is distributed in a required manner for the actuation of the pistons of the engine, and a booster or device adapted to be brought into operation to effect the rotation of the engine crank shaft should it be at rest on a dead center, in order to effect the carrying thereof beyond the dead center to a sufficient extent to permit the fluid to actuate the pistons and bring about the starting of the engine. This booster or device for promoting the starting of the engine may also be in the form of a compressor, the compressing function of which is brought into operation after the engine has been started so that it will continue to operate in the ordinary manner without the assistance of the starter. All of which is more particularly described and ascertained hereinafter, by way of example, having reference to the accompanying drawing, wherein

Figure 1 is an end elevation of an engine, to which apparatus embodying the said invention is applied, one of the auxiliary starting cylinders being shown in section;

Figure 2 is a detail rear elevation of the control valve with the cover plate removed;

Figure 3 is a transverse section of the same on the line 3x—3x Figure 2, with the cover plate in place;

Figure 4 is a similar section taken on the line 4x—4x Figure 2;

Figure 5 is a diagrammatic view illustrating the relative arrangement of the active members, and the cylinders, pistons and crank shaft of the engine;

Figure 6 is a broken detail view partly in section of a modified form of the said invention;

Figure 7 is an elevation of certain of the parts shown in Figure 6 illustrating the slightly modified arrangement thereof, and

Figure 8 is an elevation of a simple modified form of booster associated with an engine.

Similar characters of reference indicate similar parts in the several figures of the drawings.

My invention is described as being applied

to a four cylinder engine 1, the cylinders being indicated in Figure 5 as A, B, C and D and the form of starter is indicated as embodying certain elements of my prior patent 5 No. 1,481,091 granted to me on the 15th day of January, 1924 and Reissue Patents Nos. 16,695 and 16,696, of August 9, 1927. Connected with each of the engine cylinders are pipes 2, 3, 4 and 5 emanating from a valve 10 casing 6 which houses a rotary disk valve 7 which is enclosed by a cover plate 8 and is operated by a sprocket wheel 9 mounted upon the spindle 10 of the said valve, 11 being a spring housed in the said cover plate and 15 maintaining the said valve seated in its casing. 12 is an inlet pipe entering the cover plate of the said casing and branching from a pipe 13 connected to a storage tank 14 adapted to contain fluid such as air under 20 pressure, the said pipe 12 being interrupted by a manually operable valve 15 which is normally closed and may be of any suitable type, 16 being the operating button or plunger of the said valve which effects the 25 opening thereof when depressed.

The pipes 2, 3, 4 and 5 are associated with ports 17, 18, 19 and 20 in the wall of the casing 6 and the said disk valve 7 is provided with a port 21 adapted to co-act with the 30 ports 17, 18, 19 or 20 at different positions to which the said disk valve may be rotated, so that fluid under pressure may be admitted to the said cylinders in the required order on their power strokes as the said valve rotates and as will be well understood without further explanation, the rotation of the said valve being effected by means of a chain 22 extending over the sprocket 9 and a sprocket 23 which is geared to the cam shaft 24 of the 40 engine.

In the starting of the engine the depression of the plunger 16 opens the valve 15 provided the engine is not on dead center and admits fluid under pressure to one of the cylinders 45 according to the position of the valve opening 21 relative to one or other of the ports 17, 18, 19 or 20, the said valve being timed so that the port so disclosed will be one associated with one of the raised pistons ready 50 to perform the power stroke. This pressure will result in the rotation of the said crank shaft, and, the fluid under pressure being admitted to other of the cylinders in their proper order or cycle, rotation of the engine 55 will be continued until starting of the engine results; all conditions, such as ignition, being of course correct for that purpose.

Should the engine be standing on dead centers, no fluid under pressure will pass the 60 valve opening 21 or the ports 17, 18, 19 or 20, but it will pass through one of the ports 38 or 39 then through the corresponding outgoing pipe 32 or 31 into the corresponding plunger cylinder, or booster which I provide.

65 In Figure 5, the engine crank is shown on

dead centers, with the piston of cylinder A just going to begin its power stroke; the valve opening 21 at this moment is exactly between the ports 18 and 17, and therefore no fluid will pass the valve opening 21, but just in this position fluid is free to pass through port 38 and through pipe 32 to the cylinder 27. The piston 28 is then forced out and the piston rod associated with it forces the main crank shaft 25 just beyond the dead center 70 whereby the main engine cylinders begin operation, the cylinders 26 and 27 thereupon becoming compressor cylinders.

In Figures 1 and 5 this device is indicated as comprising opposed cylinders 26 and 27 enclosing pistons 28 coupled to a crank 29 on the end of the crank shaft by connecting rods 30, 31 and 32 being inlet pipes leading from ports 33 and 34 in the valve casing 6 and opening into chambers in the heads 35 and 36 of the said cylinders 26 and 27, which heads house non-return poppet valves 37.

38 and 39 are ports in the rotary valve 7 adapted to co-act with one or other of the ports 33 and 34 in the valve casing during the rotation of the said valve whereby, if the engine be at rest in a dead center position or the requisite port 17, 18, 19 or 20 be closed against the admission of fluid to the engine, one or other of the said ports 33 or 34 will be open permitting admission of fluid under pressure to one or other of the cylinders 27 or 28 so that the piston thereof may be actuated to effect the initial rotary movement of the crank shaft, which will accordingly 95 result in the opening of the required port 17, 18, 19 or 20 for the starting of the engine.

40 and 41 are inlet pipes through which the fluid enters the said cylinders 26 and 27 upon the forward motion of their pistons, 100 when acting as compressors.

The arrangement illustrated also permits of the recharging of the tank 14, after the starting up of the engine, as the booster may be utilized as a compressor as previously 110 stated, delivering fluid to the said tank through the pipes 42 and 43 by virtue of the operation of inlet and outlet valves 44 and 45 arranged in the cylinder heads 35 and 36 of the said booster.

In the arrangement of Figure 6, the compressing feature is dispensed with and a cylinder 46 is illustrated having a piston 47 therein operable by fluid under pressure against the action of a compression spring 48, the inlet and outlet to and from said cylinder being controlled by a slide valve 49 actuated by a rod 50 which is engaged by a tappet 51 on the other end of the piston rod 52 to transmit motion to the said slide valve in one direction, the motion thereof in the other direction being effected by a further tappet 53 on the said valve rod.

60 Admission of fluid under pressure to the valve chamber 54 is effected through a pipe 120

32a communicating with the valve casing 6, the rotary valve of which is provided with four orifices 55 actuating similarly to the orifices 38 and 39 and communicating successively with a single port 56 in the said valve casing to bring about the initial movement of the crank shaft 25 in case the parts are in such position that the starter would not ordinarily effect such initial movement.

10 The coupling of the piston 47 in this case to the crank shaft is intermittent and is effected through the medium of the fly wheel 57 which is notched at 58 to receive a pawl 59 mounted on the end of the piston rod 52 and 15 normally depressed by a spring 60 so that it may co-act with the said notches 58 during the forward movement of the piston 47 to effect the rotation of the said fly wheel only when the engine has its cranks on dead centers 20 or in an inoperative position, and with the assistance of the pressure operated piston 47 which is required to effect the initial rotation thereof. In this arrangement the association of the booster with the crank shaft is 25 localized due to the limited arc through which the notches 58 extend, so that this operation is only effective when the relative positions of the parts are such that assistance thereof is necessary. To prevent danger or damage 30 to the booster by back firing of the engine and consequent reversal of rotation of the fly wheel, an arm 61 is provided over which the said pawl rides and which effects the raising and disassociation of the said pawl from the 35 said fly wheel when the pawl is moved to a retracted position as shown.

In this form the booster plunger only operates when the engine crank is on dead center and this is somewhat modified in its connections in the arrangement shown in Figure 40 7 wherein instead of the pipe 32a from the valve casing 6, a direct connection from the pipe 12 is secured by means of a pipe 62 entering the valve chamber 54. In this form 45 the booster plunger always operates when the starting button is pressed; but of course only turns the engine crank when it is on dead centers.

In Figure 8 an arrangement is shown 50 whereby the auxiliary impulse device may be foot operated instead of by the fluid pressure, 63 being a support, such as the floor board of a car in which the engine may be installed, the said support carrying a frame 55 64 slotted at 65 to form a guideway for a pawl 66 mounted on the lower end of a foot operable plunger 67, which plunger may be depressed against the tension of a return spring 68. 69 is a spring adapted to depress 60 the said pawl into the notches 58 of the fly wheel 57, when the said pawl is moved beyond a pin 70 which corresponds to the arm 61 shown in Figure 6. This device, when actuated, performs a similar function to that 65 of the device illustrated in Figure 6 and is

also localized in its association with the fly wheel as will be readily seen.

Utilizing the booster or auxiliary starting device as suggested, ensures the setting in motion of an engine so equipped irrespective of dead center normally opposing the starting operation and also assists in the overcoming of initial inertia of the engine and resistance which may be offered to the starting thereof; so that a starter with which the 70 said invention is employed will be enabled to function much more readily than would otherwise be the case and will be more reliable and less subject to sticking or interruption in its operation as a result of the assistance rendered by the booster.

This invention may be developed within the scope of the appended claims without departing from the essential features of the invention, and it is desired that the specification and drawing be read as being merely 85 illustrative and not in a limiting sense, except as necessitated by the prior art.

What I claim is:

1. In combination, an engine comprising 90 a plurality of cylinders, pistons slidably mounted in said cylinders, a crank shaft connected to said pistons, a distributor adapted to supply a pressure fluid to said cylinders, a pressure tank connected to said distributor, 95 and a pressure operated turn-over device having direct fluid communication with said distributor and connected directly to said crank shaft.

2. In combination, an engine comprising a 100 plurality of cylinders, pistons slidably mounted in said cylinders, a crank shaft connected to said pistons, a distributor adapted to supply a pressure fluid to said cylinders, a pressure tank connected to said distributor, 105 a starting crank carried by said crank shaft, and a pressure operated turn-over device having direct fluid communication with said distributor and linked to said crank.

3. In combination, an engine comprising 110 a plurality of cylinders, pistons slidably mounted in said cylinders, a crank shaft connected to said pistons, a distributor adapted to supply a pressure fluid to said cylinders, a pressure tank connected to said distributor, 115 a compressor having a connection with said tank for charging the same, the movable element of said compressor being connected to said crank shaft, a further connection from said tank to said distributor and from said distributor to said compressor for starting the latter, a valve member in 120 said distributor controlling the connections to the cylinders and compressor, said valve member being geared to the engine in a manner to open the connection to the compressor when the crank shaft is on dead center.

4. In combination, an engine comprising a plurality of cylinders, pistons slidably mounted in said cylinders, a crank shaft con-

nected to said pistons, a distributor adapted to supply a pressure fluid to said cylinders, a pressure tank connected to said distributor, a compressor having a connection with said tank for charging the same, the movable element of said compressor being connected to said crank shaft, and a further connection between said tank and compressor for starting the latter, said connection passing through said distributor.

5. In combination, an engine comprising a plurality of cylinders, pistons slidably mounted in said cylinders, a crank shaft connected to said pistons, a turn-over device connected to said crank shaft, a pressure fluid distributor having fluid connections to said cylinders and turn-over device and including a valve controlling said connections, said valve being geared to the engine in a manner 15 to open the fluid connection to said turn-over device when the crank shaft is on dead center.

In testimony whereof I affix my signature.
CHARLES FREDERICK HEYWOOD.
